UNITED STATES PATENT OFFICE.

JAMES G. DICKSON, OF CHICAGO, ILLINOIS, ASSIGNOR OF ONE-THIRD TO WALTER E. WOLF, OF CHICAGO, ILLINOIS.

SPARK PLUG.

1,414,806.

Specification of Letters Patent.

Patented May 2, 1922.

Application filed July 3, 1919. Serial No. 308,589.

To all whom it may concern:

Be it known that I, JAMES G. DICKSON, a citizen of the United States of America, and a resident of Chicago, in the county of Cook, 5 State of Illinois, have invented certain new and useful Improvements in Spark Plugs, of which the following is a specification.

This invention relates to sparking plugs for internal combustion engines, and has for 10 its object:—

To provide a simple and efficient structural formation and association of parts whereby aligned multiple spark gaps are provided at the inner end of the sparking plug, with a 15 resulting increased efficiency in the explosion producing action of the same, all as will hereinafter more fully appear.

In the accompanying drawing:

Fig. 1, is a perspective view of a spark 20 plug constructed in accordance with the present invention.

Figs. 2 and 3 are fragmentary detail sections of the inner end of the spark plug, taken in planes at right-angle relation to 25 each other.

Like reference numerals indicate like parts in the several views.

Referring to the drawing, 1 designates the usual metal shell or bushing of the 30 spark plug having an externally screw-threaded lower annular sleeve portion 2 adapted for engagement in the spark plug opening of an engine cylinder, and with an internally screw-threaded upper portion 3 adapted to receive a sleeve nut 4 by which the usual central core or plug 5 of insulating material, is secured in place.

6 designates the usual conductor arranged axially in the insulating core 5 and provided 40 at its upper end with the usual binding post and nut 7 for connection with the line wire by which electro-motive force is supplied to the spark plug, as usual in this class of such appliances. At its lower end, which projects down beyond the insulating core 5 and lower annular sleeve portion 2 of the shell 1 aforesaid, the conductor 6 is formed with a laterally deflected terminal portion 8 as shown.

50 9 designates a terminal point or stem secured to the lower end of the main shell or bushing 1 and having its lower end bent towards the terminal portion 8 of the conductor 6 aforesaid.

10 designates a bridge plate of insulating 55 material attached to the lower surface of the lower sleeve portion 2 of the main shell or bushing 1, between the respective terminal points or stems 8 and 9 above described, and preferably by means of a pair of de- 60 pending saddle posts 11 as shown.

12 designates an intermediate block or stem of metal or like conductive material, secured in a horizontally adjustable manner in the bridge plate 10 aforesaid, by attaching nuts 13, with its respective ends having spaced relation to the respective terminal points or portions 8 and 9 above described, and so that the electric current will make a primary spark in its jump between the supply terminal 8 and said block 12, and make a secondary spark in its jump from said block 12 to the return terminal 9. Such multiple spark production in an approxi- 70 mately straight line, and at the lower end 75 of the spark plug wholly within the explosive mixture of the engine cylinder, is adapted to produce a certain and powerful explosion of said mixture.

Having thus fully described my said invention what I claim as new and desire to 80 secure by Letters Patent, is:—

1. In a spark plug having supply and return terminals at its lower end, the combination of a transversely extending bridge 85 plate of insulating material secured to the lower end of the spark plug by a pair of depending and diametrically opposed saddle posts, and a conducting block carried by such bridge plate in spaced relation to 90 the aforesaid supply and return terminals.

2. In a spark plug having supply and return terminals at its lower end, the combination of a transversely extending bridge 95 plate of insulating material secured to the lower end of the spark plug by a pair of depending and diametrically opposed saddle posts, and a conducting block secured in a horizontally adjustable manner to said bridge plate in spaced relation to the aforesaid supply and return terminals, and adjusting nuts at opposite sides of the bridge plate for effecting the adjustment aforesaid.

Signed at Chicago, Illinois, this 21st day of June, 1919.

JAMES G. DICKSON.
